PROCESS FOR THE RESOLUTION OF GAS MIXTURES

Mathias Fränkl, Augsburg, Germany, assignor to
 American Oxythermic Corporation, New York,
 N. Y., a corporation of Delaware

Application October 14, 1931, Serial No. 568,714
 In Germany May 20, 1931

14 Claims. (Cl. 62—175.5)

The invention relates to a process and an apparatus for the resolution of gas mixtures into component parts. It more particularly relates to a process for the separation of air into oxygen and nitrogen and includes correlated improvements and discoveries whereby the separation of oxygen and nitrogen is enhanced.

The invention is in certain of its characteristics similar to that described in my co-pending application, Serial No. 437,204, filed March 19, 1930 and which issued as Patent No. 1,970,299, August 14, 1934. In this application there is described a process wherein the loss of compression energy which is entailed in the total compression of the gas mixture necessary for carrying out an efficient sublimation effect of deposited H_2O and CO_2 is reduced by not liquefying a certain portion of the compressed gas mixture, but detensioning it in an expansion engine to atmospheric pressure, while performing work and yielding cold, and preferably after previous preliminary resolution of the gas mixture in a rectifier operated at the condensation pressure. It may also be effected with a subsequent resolution of the exhaust of an expansion engine in a rectifier which operates at atmospheric pressure. In both cases therefore, the total air to be resolved is compressed to the condensation pressure, i. e. 3 to 5 atmospheres absolute, and about one-half to three-quarters thereof is liquefied in order to obtain the necessary washing liquid, while the other portion is detensioned in an expansion engine in order to produce the additional cold required for covering the cold losses.

It is an object of the invention to provide a process in which the loss of compression energy normally occurring during the resolution of a gas mixture with total compression is reduced.

It is a further object of the invention to provide a process for the separation of oxygen and nitrogen from air in which only a part of the air is compressed to condenser pressure, the other portion being simply blown in.

Another object of the invention is to provide a process with reduced compression losses and which is applicable for the production of oxygen of various degrees of purity, as for example a 42 per cent or a 47 per cent oxygen containing mixture.

A further object of the invention is to provide a process in which an exchange of cold is effected between the ingoing air and the outgoing separated components by means of regenerators with alternate periodical reversal.

It is also an object of the invention to provide

an apparatus suitable for effecting separation of gas mixtures into component parts and comprising means for effecting a reduction in compression and cold losses.

Other objects of the invention will in part be obvious and will in part appear hereinafter.

The invention accordingly comprises the several steps and the relation of one or more of such steps with respect to each of the others, and the apparatus embodying features of construction, combinations of elements and arrangement of parts which are adapted to effect such steps, all as exemplified in the following detailed disclosure, and the scope of the invention will be indicated in the claims.

For a fuller understanding of the nature and objects of the invention reference should be had to the following detailed description taken in connection with the accompanying drawings, in which:

Fig. 1 illustrates diagrammatically an arrangement of apparatus in which the process may be practiced with withdrawal of a portion of the compressed air prior to liquefaction, and

Fig. 2 shows diagrammatically an apparatus in which the process may be practiced utilizing a portion of the compressed air after resolution for further cooling and expansion to compensate for compression loss.

In the practice of the invention a reduction in the loss due to compressing the entire gas mixture to condenser pressure i. e., the pressure at which liquefied gas is produced under prevailing conditions of cold, such as normally occurs during the resolution of air, is effected by compressing only one-half of the air to be resolved to the condensation pressure, this pressure furthermore being reduced by about one-third by withdrawing the oxygen from the vaporizer at a reduced pressure of about 0.6 atmosphere absolute. The other half of the air to be resolved is blown, without excess pressure, into an upper column, in which rectification takes place at approximately atmospheric pressure.

The compression necessary for the resolution of the air is therefore subdivided in such a manner that the compression is carried out to about one-half before the resolution and thereafter the other half takes place in that the oxygen which is removed from the vaporizer by suction at 0.6 atmosphere absolute is compressed to atmospheric pressure.

In this way a sufficient difference in volume for the complete sublimation effect is obtained for one-half of the air to be resolved, is led at about

- 2 atmospheres absolute through one pair of C., and is blown in at the bottom of an upper rectification column.
- As a result, the excess 10 parts or per cent of compressed air finally are utilized as blast air, thereby creating the quantitative equalization 5 for the operation of the cold storage devices. In this manner, the amount of blast air lacking can be introduced through the nitrogen cold storage device, for which there would otherwise be an excess of nitrogen to be led out. Hence, only so 10 much blast air need be led through the oxygen cold storage device as corresponds to the amount of oxygen which is led out.
- This procedure differs from that of my co-pending application in that the excess portion of 15 air compressed to condensation pressure and which is removed unliquefied from the low cooling zone of the apparatus in order to be detensioned in the expansion engine, is further compressed before it enters the expansion engine, 20 after being previously warmed to atmospheric temperature by cold exchange with itself and is then again cooled to about -100°C .
- The accompanying drawings illustrate an arrangement suitable for carrying out the process. 25
- Referring to Fig. 1, fifty-five per cent (in round numbers) of the amount of air to be resolved, at a pressure of about 2 atmospheres absolute, are led through lines 1', 1'' and 2 alternately through cold storage devices A' and A'', and an equally 30 large amount of separated nitrogen is led out through line 3, 4' and 4'' at atmospheric pressure.
- The compressed air, to the extent of about 80 per cent, is resolved in pressure column b' into 43 per cent oxygen and almost pure nitrogen, where- 35 by there is produced from about one-half of the compressed air by liquefaction on the condenser side c of vaporizer c', a liquid with an oxygen content of about 43 per cent, and as to the other half, liquid nitrogen. The 43 per cent oxygen liquid 40 is now conveyed through line 5 into the lower quarter of the upper rectification column b'' and the liquid nitrogen through line 6 to the uppermost tray of the same. On their way to the upper rectifier both liquids are led through the after-coolers p (for the 43 per cent oxygen liquid) and r (for the liquid wash nitrogen), and are cooled by the gaseous nitrogen passing out of the upper column b'' through line 3.
- About 45 per cent of the air to be resolved is 50 led, at a pressure of about 0.1 atmosphere gauge by line 1', 1'' and 8 alternately through cold storage devices B' and B'', and an equal amount of oxygen of an oxygen content of about 47 per cent is led out at a reduced pressure of 0.6 atmos- 55 phere absolute through line 9, 10' and 10''. The blown-in air is introduced through line 8 into the bottom of the upper column, and flowing up through the latter is led counter-current, first to the 43 per cent oxygen liquid and then to the 60 liquid nitrogen, whereby the oxygen is washed out of the blown-in air and both liquids are enriched to an oxygen content of about 47 per cent.
- The portion of about 20 per cent of the compressed air which is not liquefied is led out 65 through line 11, first through a cold exchanger d, then through an air liquefier f, and finally through an additional cold exchanger g whereby this portion is heated to about atmospheric temperature. It is then compressed in compressor h 70 to from 10 to 15 atmospheres absolute, led through line 12 again into cold exchanger g, where it is forecooled to about -100°C ; conducted through line 13 into expansion engine k; detensioned in the latter almost to atmospheric 75
- According thereto a complete sublimation of the hoar frost which freezes out of the air led into the cold storage devices as a result of the content of moisture and carbon dioxide, and which is temporarily deposited there, can be brought about without loss of energy.
- If oxygen is to be recovered with an oxygen content of 42 per cent in the mixture produced, then the amounts compensate one another exactly, for one-half of the resolved air will come out of the apparatus as a mixture rich in oxygen, and the other half as nitrogen, so that it is possible to introduce one-half of the air into each of the two pairs of cold storage devices. The one half is compressed and liquefied and serves as wash liquid, the other half is blown in and the oxygen is washed out of it by the wash liquid.
- When, however, a mixture richer in oxygen than a 42 per cent oxygen content is required, there is created a lack of agreement in the relative amounts of blast air-oxygen mixture and compressed air-nitrogen, for the more oxygen the mixture is to contain the more nitrogen is separated out and the smaller is the amount of the mixture rich in oxygen.
- If, for example, a mixture with a 47 per cent oxygen content is demanded, 0.55 cubic meter of nitrogen is separated per cubic meter of total air throughput, and 0.45 cubic meter of mixture with a 47 per cent oxygen content is recovered.
- The enrichment of the wash liquid (which in this case consists of pure, liquid nitrogen) to 47 per cent oxygen requires 55 parts of blast air, while for the production of a 45 per cent oxygen mixture only 45 parts of compressed air are required. Accordingly, 55 parts of nitrogen must be led out through that pair of cold storage devices through which only 45 parts of compressed air can alternately be introduced and, on the other hand, 55 parts of blast air are alternately to be led counter-current through another pair of cold storage devices with respect to the 45 parts of oxygen mixture, which, of course, is not balanced with regard to the thermal equilibrium of the cold storage devices.
- To equalize this lack of agreement more compressed air is led in through the one pair of cold storage devices than is actually needed for the formation of the necessary wash liquid, that is 55 parts instead of 45.
- The ten parts of compressed air introduced in excess are again taken out of the resolution apparatus unliquefied at a pressure of 2 atmospheres absolute. They are first led through a counter-current cold exchanger, then through an air liquefier, and supplementarily are led through a counter-current cold exchanger, compressed further in a compressor to 10 to 15 atmospheres absolute, and again conducted through the cold exchanger in order to be forecooled in the latter to about -100°C . Subsequently they are detensioned to atmospheric pressure in an expansion engine, whereby they are cooled to -170°C . The exhaust is then after-cooled in the first mentioned counter-current cold exchanger to about -190°C .

pressure, and is blown through cold exchanger *d* and line 14 as exhaust into the upper column *b*'. The nitrogen, separated in a gaseous state, is led off at atmospheric pressure from the top of the upper column through line 3, passed through the after-coolers *r* and *p* and led out alternately through cold storage devices *A'* and *A''*, while the oxygen, with an oxygen content of about 47 per cent, is removed under suction through line 10 9 from the vaporizer side *c'* of condenser *c*, at 0.6 atmosphere absolute, alternately through cold storage devices *B'* and *B''*.

Instead of conducting the excess compressed air to an expansion engine and resolving the exhaust in the upper rectifier, this portion of the air can also be resolved in the lower rectifier at the condensation pressure and unliquefied nitrogen for the operation of the expansion engine is taken out of the pressure column through line 11 (Fig. 2), which nitrogen is then likewise led through cold exchanger *d*, liquefier *f* and cold exchanger *g* at about 2 atmospheres absolute whereby it is warmed to about atmospheric temperature; compressed further to 10 to 15 atmospheres absolute; led through line 12 into cold exchanger *g* where it is forecooled to about -100° C., and is then led through line 13 into expansion engine *K* and detensioned to atmospheric pressure in the latter. After further cooling to about -185° C. in exchanger *d*, it is led through line 14 (Fig. 2) into cold storage devices *A'* and *A''* and is led through the latter out of apparatus. In this way, the necessary amount of blast air can likewise be brought into agreement with the amount of oxygen led out because a larger amount of oxygen is thereby produced in the pressure column, and less liquid wash nitrogen is poured in at the top of the upper column in an amount corresponding to that of the nitrogen which is withdrawn in a gaseous state from the pressure column for the operation of the expansion engine.

Therefore, the increased amount of oxygen produced in the pressure column without an increased amount of blast air, on the one hand, produces a saving of blast air and, on the other hand, the requirement of blast air is further diminished by the diminished amount of liquid wash nitrogen which is poured in at the top of the upper column.

This mode of operation differs from the form in Fig. 1 only in that air from the bottom of the cold storage devices is not used for the operation of the expansion machine and the exhaust subsequently resolved by blowing into the upper column, but that pressure nitrogen is taken from the pressure column in a gaseous state in order, after warming and greater compression with subsequent forecooling, to be detensioned in the expansion engine, and is then led out through the cold storage devices, after having previously been after-cooled by the pressure nitrogen to about -185° C.

According to this procedure the resolution of that portion which performs work in the expansion engine takes place before the detensioning and at an excess pressure, and nitrogen, instead of air, is led into the expansion engine.

A certain amount of highly compressed air is led into liquefier *f* at *z*, after having previously been forecooled to -45° C. in an ammonia refrigerating machine (not shown) and is liquefied by the portion of compressed air or nitrogen led out, in order to cover the unavoidable losses of cold.

The supplementary liquid is led through line 15 into pressure column *b*'.

The procedure of the present invention is characterized in that instead of the gas mixture being totally compressed, only about one-half is compressed, whereas the other half is blown in. The compressed portion is compressed to only about one-half the extent required where a straight compression process is utilized. Further, the difficultly boiling separated product is removed under reduced pressure from the evaporator side of the condenser and that portion of the gas mixture which is simply blown in uncomplicated traverses that pair of cold storage devices or regenerators through which the difficultly boiling separated product is led out. This produces with respect to the amount of gas mixture which is blown in uncomplicated, the necessary difference in volume for a complete sublimation of deposited water and carbon dioxide in the regenerators without requiring the compression of a greater part of the gas mixture than is necessary to carry out the separation process. Also the recovery of oxygen with an oxygen content greater than 45 per cent is effected by compressing a portion of the gas mixture greater than that required for the formation of the wash liquid and conveying this added portion of the gas mixture to an expansion engine after it has been warmed, further compressed and cooled to about -100° C. Furthermore, the exhaust from the expansion engine is cooled to a greater extent by cold exchange with the excess compressed portion of the gas mixture or with the more easily boiling constituent thereof before it is conducted through the regenerators or led into the upper rectification column.

Since certain changes in carrying out the above process and in the constructions set forth, which embody the invention may be made without departing from its scope, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent is:

1. A process for the resolution of gas mixtures which comprises introducing a portion of a gas mixture compressed to condenser pressure through a regenerator previously cooled by means of an easily boiling component of said mixture to a rectifier, introducing another portion of said gas mixture uncomplicated through a regenerator previously cooled by a difficultly boiling component into another rectifier, conducting liquid formed in said first rectifier to said second rectifier, conveying difficultly boiling component liquid from the second rectifier to the vaporizer side of a condenser and withdrawing separated difficultly boiling component therefrom under reduced pressure, removing a portion of the compressed and cooled gas mixture, warming said removed portion by heat exchange with an added quantity of gas mixture which is introduced into said first rectifier, compressing, cooling, and detensioning to recover cold given up to the additional quantity of gas mixture, and reintroducing into the process whereby cold and compression losses are reduced.

2. A process for the resolution of gas mixtures which comprises introducing a portion of a gas mixture compressed to a condenser pressure

through a regenerator previously cooled by means of an easily boiling component of said mixture to a rectifier, introducing another portion of said gas mixture uncompressed through a regenerator previously cooled by a difficultly boiling component into another rectifier, conducting the liquid from said first rectifier to said second rectifier, conveying difficultly boiling component liquid from the second rectifier to the vaporizer side of a condenser, withdrawing the separated difficultly boiling component therefrom under a reduced pressure of about 0.6 atmosphere absolute, removing a portion of the compressed gas mixture and then warming said removed portion by heat exchange with an additional quantity of gas mixture which is then introduced into said first rectifier, compressing, cooling, and detensioning to recover cold given up to the additional quantity of gas mixture, and reintroducing into the process whereby cold and compression losses are reduced.

3. A process for the resolution of air into oxygen and nitrogen which comprises compressing a portion of the air to condenser pressure, passing said compressed air through a regenerator which has previously been cooled by outgoing nitrogen, introducing the compressed and cooled air into a rectifier, passing another portion of air uncompressed through a regenerator which has previously been cooled by outgoing oxygen, introducing said cooled air into another rectifier, conveying liquid from said first rectifier to said second rectifier, leading oxygen liquid from said second rectifier to the vaporizer side of a condenser in said first rectifier and removing oxygen therefrom under reduced pressure, removing a portion of the compressed and cooled air, warming said removed portion by heat exchange with an added quantity of air which is then introduced into said first rectifier, compressing, cooling and detensioning to recover cold given up to the additional quantity of air, and reintroducing into the process whereby cold and compression losses are reduced.

4. A process for the resolution of air into oxygen and nitrogen which comprises compressing a portion of air to a pressure of about 2 atmospheres, passing said compressed air through a regenerator previously cooled with nitrogen and introducing said air into a rectifier; passing a portion of uncompressed air through regenerators previously cooled by outgoing oxygen and introducing said uncompressed air into another rectifier; conducting liquid formed in the first rectifier to the second rectifier, conveying oxygen liquid from the second rectifier to the vaporizer side of a condenser in the first rectifier, removing oxygen therefrom under a reduced pressure of about 0.6 atmosphere absolute, removing about 10 per cent of the compressed air prior to rectification, passing said air through a plurality of heat exchangers whereby it is warmed including transfer of heat from an additional quantity of air thereto, thus liquefying the air, introducing the thus liquefied air into said first rectifier, compressing to from 10 to 15 atmospheres absolute, cooling to about -100° C., detensioning in an expansion engine to about atmospheric pressure, whereby it is cooled to about -170° C. to recover cold given up to the additional quantity of air, further cooling to about -190° C. and introducing into said second rectifier whereby cold and compression losses are reduced.

5. A process for the resolution of gas mixtures into components, which comprises rectifying a

portion of a gas mixture compressed to condenser pressure and cooled in a first rectifier, whereby lower boiling component in gaseous form and higher boiling component in liquid form are separated, rectifying liquid so produced in a second rectifier under substantially atmospheric pressure, withdrawing separated higher boiling component under a reduced pressure, removing a portion of the compressed gas mixture, warming said removed portion by heat exchange with an added quantity of gas mixture which is then introduced into said first rectifier, compressing, cooling and detensioning to recover cold given up to the additional quantity of gas mixture, and reintroducing into the process whereby cold and compression losses are reduced. 5

6. In a process for the resolution of air into nitrogen and oxygen, the improvement which comprises compressing air to about 2 atmospheres, cooling in a regenerator, withdrawing a portion of the compressed and cooled air prior to resolution in a first rectifier separating the remaining portion of the cooled air in said first rectifier wherein liquid enriched in oxygen is obtained and subsequently resolved into nitrogen and oxygen 25 in a second rectifier, rearming said portion by heat exchange with an additional quantity of air which is then introduced into said first rectifier, compressing, cooling and detensioning to about atmospheric pressure to recover cold given up to the additional quantity of air, further cooling, and then introducing into the second rectifier whereby cold and compression losses are reduced. 30

7. In a process for the resolution of a gas mixture, the improvement which comprises compressing a gas mixture to condenser pressure, cooling in a regenerator, removing a portion of said compressed and cooled mixture, rearming said portion by heat exchange with an additional quantity of gas mixture which is subsequently 35 subjected to resolution, compressing, cooling, then detensioning to recover cold given up to the additional quantity of gas mixture whereby cold and compression losses are reduced, reintroducing into the process, and separating into components. 40

8. In a process for the resolution of air into nitrogen and oxygen, the improvement which comprises compressing air to about two atmospheres, cooling in a regenerator, withdrawing a portion of the compressed and cooled air prior to resolution in a first rectifier separating the remaining portion of air in said first rectifier whereby a liquid enriched in oxygen is obtained and subsequently resolved into nitrogen and oxygen 55 in a second rectifier, rearming said portion by heat exchange with an additional quantity of air which is subsequently subjected to resolution, compressing to a pressure of about 10-15 atmospheres absolute, cooling to a temperature of about 60 -100° C. and detensioning in an expansion engine to about atmospheric pressure to recover cold given up to the additional quantity of air; further cooling by countercurrent exchange with a portion of air immediately after it is withdrawn 65 from the main body to a temperature of about -190° C., and then introducing into a second rectifier whereby cold and compression losses are reduced. 60

9. In a process for the resolution of a gas mixture, the improvement which comprises compressing a gas mixture to condensation pressure, cooling in a regenerator, removing a portion of said compressed and cooled mixture, rearming said portion including transfer of heat from an 75

additional quantity of gas mixture thereto whereby the gas mixture is liquefied, introducing the thus liquefied gas mixture into the resolution process, compressing the removed and warmed portion, cooling, detensioning to recover cold given up to the additional quantity of gas mixture, and then cooling further, reintroducing into the process, and separating into components.

10. In a process for the resolution of air into components, the improvement which comprises compressing air to condensation pressure, cooling in a regenerator, removing a portion of said compressed and cooled air, rearming said portion including transfer of heat from an additional quantity of air thereto whereby the air is liquefied, introducing the thus liquefied air into the resolution process, compressing the removed and warmed portion, cooling, detensioning to recover cold given up to the additional quantity of air, and then cooling further to a temperature of about -190° C., reintroducing into the process and separating into components.

11. An apparatus for resolution of gas mixtures comprising in combination a plurality of regenerators having regenerative packing, means for effecting separation of the gas mixture into components, conduits for conducting the gas mixture from the regenerators to the separating means and from the separating means to the regenerators, conduits for charging gas mixture to the regenerators and for discharging separated components therefrom, a conduit connected with said separating means for conveying a portion of the gas mixture to a series of heat interchangers, said conduit connecting with a coil in a first exchanger, said coil connected with the outer space of a second exchanger by means of a conduit, a conduit leading from the outer space of said second exchanger to the outer space of a third exchanger, a coil within said second exchanger through which an additional quantity of gas mixture may be conducted and cooled, a conduit for conducting said added gas mixture to the separating means wherein it is subjected to resolution, a compressor in communication with the outer space of and with a coil in the third exchanger, a conduit leading from the coil in the third exchanger to an expansion engine, a conduit connecting said expansion engine with the outer space of said first exchanger, and a conduit leading from the outer space of said first exchanger for re-introducing said portion of gas into the system whereby cold and compression losses are reduced.

12. In an apparatus for the resolution of gas mixtures, a cooling and separating system in combination with a conduit for conveying a part of the gas mixture to a series of heat exchangers, said conduit connecting with a coil in a first exchanger, said coil connected with the outer space of a second exchanger by means of a conduit, a conduit leading from the outer space of said second exchanger to the outer space of a third exchanger, a coil within said second exchanger through which an additional quantity of gas mixture may be conducted and cooled, a conduit for conducting said additional gas mixture to the separating means wherein it is subjected to resolution, a compressor in combination with the outer space of and with a coil in the third exchanger, a conduit leading from the coil in the third exchanger to an expansion engine, a conduit connecting said expansion engine with the outer space of said first exchanger, and a conduit leading from the outer space of said first exchanger for re-introducing said portion of gas into the system whereby cold and compression losses are reduced.

13. A process for the resolution of a gas mixture into components, which comprises rectifying a gas mixture compressed to condenser pressure and cooled, in a first rectifier, whereby lower boiling component in gaseous form and higher boiling component in liquid form are separated, rectifying the liquid so produced in a second rectifier, withdrawing separated higher boiling component, removing a portion of compressed and cooled gas, warming said removed portion including heat exchange with an added quantity of gas mixture which is then introduced into said first rectifier, compressing, cooling and detensioning to recover cold given up to the additional quantity of gas mixture, and reintroducing into the process whereby cold and compression losses are reduced.

14. In a process for the resolution of a gas mixture, the improvement which comprises compressing a gas mixture to condenser pressure, cooling by passing through a cold yielding zone, removing a portion of compressed and cooled gas, re-warming said portion including heat exchange with an additional quantity of gas mixture which is subsequently subjected to resolution, compressing, cooling, then detensioning to recover cold given up to the additional quantity of gas mixture, and reintroducing into the process whereby cold and compression losses are reduced.

MATHIAS FRÄNKEL.
